UNITED STATES PATENT OFFICE.

JERVIS R. HARBECK, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

DREDGING-CAN.

1,203,872.

Specification of Letters Patent.

Patented Nov. 7, 1916.

Application filed November 22, 1909. Serial No. 529,426.

To all whom it may concern:

Be it known that I, JERVIS R. HARBECK, a citizen of the United States of America, residing in the city of Detroit and county of Wayne, State of Michigan, have invented certain new and useful Improvements in Dredging-Cans, of which the following is a specification, reference being had therein to the accompanying drawings.

10 The invention relates to dredging cans, and consists in the construction and arrangement of the perforated top and the cover therefor, as more fully hereinafter described and pointed out in the claim.

15 In the drawings—Figure 1 is a vertical central section through a can, embodying my invention; Fig. 2 is a perspective view showing my improved top, with the cover detached therefrom; and Fig. 3 is a similar 20 view of the cover for the top. Fig. 4 is a detail enlarged, vertical, sectional view of the upper portion of the dredging can and showing the method of connecting the top and cover to the body.

25 In constructing dredging cans designed to hold bath powder, cleansing powder, and the like, it is desirable—in order to reduce the cost of the can—to form the can body of pasteboard, or heavy paper, while the 30 closures for the ends of the body portion are formed of metal. As the closures have a tendency to pull, or tear out from the paper body portion, they are preferably formed dish-shaped, thereby giving a comparatively 35 large bearing surface against which the end portions of the body can be clamped. Thus, as shown, A is the can body, formed of pasteboard, and B the bottom, which is of the usual dish-shape, and fits tightly within 40 the lower end of the can. The annular flange C of the dished bottom has a re-bent portion D, which engages the end of the body, and is rolled or otherwise bent to clamp the latter against the flange C. How-

45 ever, if the perforated top was formed dish-shape, it would be positioned below the plane of the upper edge of the can body, and this would be objectionable in dredging cans, in which it is desired to control the 50 apertures in the perforated top by a rotary cover, since—in order to easily rotate the cover—it is preferably positioned above the

plane of the upper edge of the body portion, so as to be readily grasped by the hand of the operator. In order to permit the 55 cover to be positioned above the plane of the upper edge of the body of the can, and at the same time obtain the advantage of the wide bearing surface against which the end portions of the can body are clamped formed 60 by the vertical flange of the disk closure, I form the top with a raised portion E provided with one or more perforations F. This raised portion is connected by a laterally-extending flange G with an annular 65 vertical flange H, which fits tightly within the upper end of the can and forms a wide bearing surface against which the upper end of the can body is clamped by the rebent portion I of the flange H. The raised portion E, when the top is secured to the can body, preferably projects a slight distance above the plane of the upper edge of the body of the can. J is a perforated rotary cover for controlling the apertured portion 70 E and is provided with an annular flange K engaging the flange I for securing the cover to the can, but the engagement is such as to permit the cover to be rotated.

What I claim as my invention is,—

In a dredging can, in combination: a fiber body; a sheet metal top formed with an upwardly bulged and perforated central portion, an outer channel portion, a vertical flange fitting the interior of the body and a 85 seam flange which is crimped into the exterior of the end of the fiber body so as to permanently compress and secure the same against said vertical flange of the top; and a 90 perforated outwardly bulged cover the central portion of which fits on the bulged portion of said top and extends over said channel portion and seam flange of the top, said cover being formed with a marginal flange bent downwardly and inwardly to embrace 95 the exterior of the said seam flange, to rotatably hold the cover to the top.

In testimony whereof I affix my signature in presence of two witnesses.

JERVIS R. HARBECK.
